UNITED STATES PATENT OFFICE.

JAMES E. LEADLEY, OF CAMDEN, NEW JERSEY, ASSIGNOR OF ONE-HALF
TO JOHN HANLON, OF NEW YORK, N. Y.

APPARATUS FOR GENERATING HEATING OR ILLUMINATING GAS.

SPECIFICATION forming part of Letters Patent No. 289,278, dated November 27, 1883.

Application filed May 29, 1883. (No model.)

To all whom it may concern:

Be it known that I, JAMES E. LEADLEY, of Camden, in the county of Camden and State of New Jersey, have invented certain new and useful Improvements in Apparatus for Generating Heating and Illuminating Gas; and I do hereby declare that the following is a full, clear, and exact description of the invention, which will enable others skilled in the art to which it appertains to make and use the same, reference being had to the accompanying drawings, and to the letters of reference marked thereon, which form part of this specification.

15 This invention relates to the manufacture of illuminating or heating gas by the decomposition of steam, distillation of soft or bituminous coal, and the vaporization of hydrocarbon oil, and by subsequently fixing the mixture of gases and vapors.

The object is to produce a more compact, efficient, and economical apparatus for better commingling the gases and vapors and converting them into a fixed gas, and for better 25 utilizing the heat, than has been accomplished in apparatus heretofore used.

In carrying out my invention the bed of fuel in the generating-chamber is raised to a state of incandescence by blasts of air, and the 30 resulting gaseous products containing combustible carbonic oxide are burned in the commingling and vaporizing chamber and in the fixing or converting chamber by blasts of air, and the hot products of complete combustion are finally conducted through a steam-boiler for utilizing all their heat. The apparatus having been heated up, steam is admitted to and decomposed in the incandescent fuel, the resulting gases are conducted into 35 the commingling-chamber, where they are enriched with the vapors of a liquid hydrocarbon, and the mixed gases and vapors are then conducted into and through the peculiar fixing-chamber, where they are converted into 40 a fixed homogeneous gas; and the completed gas is finally conducted through the steam-boiler into the hydraulic main or seal-box, from which it is passed to the purifiers on its 45 way to the holder. Small charges of bituminous coal are periodically dropped upon the

coked incandescent fuel in the generator and distilled, yielding a large volume of rich gas, which is mixed with the gases resulting from the decomposition of steam, and is thus reduced to coke, which is used for decomposing 55 the steam. The oil is forced in measured quantities, by air-pressure, into the vaporizing and commingling chamber.

My apparatus is of peculiar and novel construction, and the improvement therein constituting my invention will be pointed out in the claims.

Having stated the nature and object of my invention, I will now more particularly describe it with reference to the accompanying 65 drawings, in which—

Figure 1 represents an elevation of the entire apparatus. Fig. 2 represents a longitudinal vertical section thereof, with the oil and air tanks in elevation. Fig. 3 represents a horizontal section of the apparatus. Fig. 4 is a view, on an enlarged scale, of the top of the generator and fixing-chamber, showing the charging apparatus with portions broken away. Fig. 5 is a plan view thereof; and Fig. 6 is a horizontal section thereof, showing the air-inlet pipes connected with the generating-chamber, the commingling and vaporizing chamber, and the converting or fixing chamber.

The generator A is of the usual construction, having a tight-fitting ash-pit door, a, and having a flue, b, connecting at its top and extending down through the wall to the base of the vaporizing and commingling chamber B. 85 Within chamber B is erected the vertical vaporizing cylinder or retort C, having an open flaring or trumpet-shaped mouth at the top, and connecting at the bottom by pipe D with the converting and fixing chamber. The vaporizer has near its top a conical oil-distributer, e, resting upon lugs or an annular flange projecting from the inside of retort, and the enlarged mouth of the oil-inlet pipe g projects down over the distributer. Below the distributer are placed the open-work or cellular commingling devices c', formed of bars or slats of fire-brick in the form of double cones. A dome, b', is mounted on chamber B, for supporting the oil-inlet pipe g. The converting 95 100

and fixing chamber E has a smoke-stack, e, with a tight-fitting lid opening into a funnel above, and has arranged internally a central cylindrical flue, F, provided with an external 5 spiral flange, f, extending from its top to bottom and between the flue and the inner surface of the walls of the chamber. The flue F is open at the top and connects at the bottom by a short flue, H, with the large central flue, H', of the steam-boiler K. The boiler is of the flue and tubular variety, having a large central flue, H', for the passage of hot gases and waste products of combustion from the generating apparatus, and also having a fire-box 10 and the ordinary tubes and stack. It forms the subject of a separate application, and is therefore not herein specifically described.

A pipe, L, and branch l conduct gas into the hydraulic seal-box L', from which it is 20 passed by pipe l" to the purifiers or holder, and a rising branch, l', having a tight-fitting lid at the top, conducts waste products of combustion to the funnel above. The boiler is provided on the outside with the usual pressure gage, water-gage, and safety-valve, and a pipe, k, rising from the dome connects with generator A and with the engine of the air-pump d by a branch, k'. Air-pipes X, having valves x, connect with the base of generator A, commingling-chamber B, and fixing-chamber E, for supplying air to support combustion in those chambers. Hydrocarbon oil is supplied to the vaporizing-retort C by pipe g from a pressure-tank, G. An air-pump, d, 30 and a reservoir, I, connected by a pipe, I', having a controlling-valve, are connected to oil-tank by pipe I, having valve i. The air-pipe opens into the top of the oil-tank, supplying air under pressure to the surface of the oil, while the outlet oil-pipe g extends down to near the bottom of the tank, where its end is open, in order to conduct oil forced by air-pressure as long as any oil remains in the tank. Pipe g' conducts oil into the tank. The pipe 40 g is provided with a pressure-gage, g", a valve, g'', and a meter, G'. The generating-chamber A has mounted upon its top the charging apparatus A', consisting of three cylinders secured in a pivoted revolving plate, and having 45 a water-cooled base and a chute connecting the cylinders with the interior of the furnace. So far as described the charging apparatus forms the subject of claims in another application; but in addition to the three coal-cylinders, there is provided a fourth short 50 cylinder, M, having a cover and a stirring-rod, N, passing through it, by which the coal in the furnace may be loosened up and broken, should it adhere together or form arches during the distilling and coking operation. A 55 charge of coal is deposited in the generating-chamber by turning a cylinder filled with coal so as to register with the chute, when the charge slides by gravity down into the chamber. The valves of the air and steam pipes are provided with rods extending upward, in 60

order to be operated from a floor above, if desired.

In operating the apparatus a fire is started in the generator, and the combustion urged by 70 a blast of air till a bed of incandescent fuel is obtained, and at the same time the gaseous products given off from the fuel are burned by blasts of air in the commingling and vaporizing chamber B and in the fixing-chamber E, 75 raising them to a high temperature, and the waste products, still hot, are conducted through the boiler and out of the stack. In case the heat of the waste gases is not required in the boiler, such gases are passed out of stack e at 80 the top of chamber E. The apparatus having been heated, the air is shut off, the smoke-stacks closed, and the steam is admitted to the base of the generator and passed up into the 85 incandescent bed of fuel, where it is decomposed, and the resulting gases, together with gas distilled from the coal, are conducted into the commingling and vaporizing chamber, where at this time oil is admitted into the distributor e of the vaporizer. The hot gases from the generator pass up around the vaporizing-retort C, and then entering at the open mouth thereof pass down with the oil-vapors through the cellular commingling devices c', the gases serving to carry the oil-vapors along 90 and preventing their deposit in the form of hard carbon or lamp-black on the sides of the chamber and flues. The mingled gases and vapors pass thence into the chamber E, where they pass through the long spiral channel 95 around the cylinder F, and then down through the cylinder, during which passage they are fully combined and converted into a fixed gas. This gas passes through the boiler, down into the hydraulic seal-box, and thence to the purifiers or holder. By means of the meter G', the quantity of oil supplied to the vaporizing-chamber is accurately measured, and the required supply is secured by means of the controlling-valve in the supply-pipe. By means 100 of the reservoir I, a constant and uniform pressure of air is supplied from the pump to the top of the oil-tank. This does away with the inconvenience and dangers of an elevated oil-supply tank.

The generating-chamber and the commingling and vaporizing chamber are preferably formed in one fire-brick structure covered by tightly-riveted plates of boiler-iron, and the fixing-chamber is formed in a closely-connected fire-brick structure, also covered with tightly-riveted plates of boiler-iron.

Having described my invention, what I claim, and desire to secure by Letters Patent, is—

1. In combination with the generating-furnace and the charging apparatus, the short cylinder M, having a stirring-rod passing through its cover, and mounted upon a pivoted revolving plate with the coal-cylinders, 130 whereby it may be brought into position over the charging-chute, so that the rod may be

thrust into the coal for stirring and breaking it up, and then turned away from heated opening.

2. In combination with the generator, the 5 commingling and vaporizing chamber having a central cylinder or retort open at the top, and provided with a distributor, *c*, and the cellular commingling devices *c'* and the oil-supply pipe, as and for the purpose described.

10 3. In combination with a generator and a commingling and vaporizing chamber, the fixing-chamber connected to the vaporizer by a tube at the bottom, and having a central cylinder open at the top, and provided with a 15 spiral flange extending between it and the wall of the chamber, as and for the purpose described.

4. The fixing-chamber having an inlet-flue at the bottom and a stack and tight-fitting 20 cap at the top, and having a central flue or

cylinder open at the top, and having a discharge-pipe passing through the outer wall of the chamber at the bottom, and provided with a spiral flange forming a spiral passage between the cylinder and the wall of the chamber, in combination with a generator. 25

5. The combination of the generator, the commingling and vaporizing chamber having a central cylinder open at the top, the fixing-chamber having a central flue and spiral flange, 30 and a steam-boiler having a central flue and the connecting-pipes, as and for the purpose described.

In testimony that I claim the foregoing as my own I affix my signature presence of two 35 witnesses.

JAS. E. LEADLEY.
